DESIGN FOR A TENNIS SHOE

John E. Hard, Cranston, R. I., assignor to Good-year Footwear Corporation, Providence, R. I., a corporation of Delaware

Application April 23, 1941, Serial No. 100,582

Term of patent 14 years

To all whom it may concern:

Be it known that I, John E. Hard, a citizen of the United States, residing at Cranston, in the county of Providence and State of Rhode Island, have invented a new, original, and ornamental Design for a tennis shoe, of which the following is a specification, reference being had to the accompanying drawing, forming part thereof.

Figure 1 is a side elevational view of a tennis shoe, showing my new design, the opposite side presenting substantially the same appearance as the side shown; and

Figure 2 is a front elevational view of the same. My design for a tennis shoe is characterized by a sole portion of varying thickness to provide a substantially flat bottom on the shoe with the heel portion of the sole thicker than the fore-part portion.

I claim:

The ornamental design for a tennis shoe, substantially as shown and described.

JOHN E. HARD.
